UNITED STATES PATENT OFFICE

CHARLES HENLEY KNIGHT, OF NORTH CARLTON, VICTORIA, AND PHIL RANDALL, OF MELBOURNE, VICTORIA, AUSTRALIA

THEATER CHAIR ATTACHMENT

Application filed August 6, 1930, Serial No. 473,435, and in Australia May 29, 1930.

This invention relates to an attachment to chairs and the like used in theaters and other places frequented by the public whereby certain useful information can be shown and 5 advertisements displayed.

The attachment consists of a light frame that can be secured to the top of the back of a chair such as one of a number constituting a fixed row in a theater or hall. Attached 10 to the frame is a plate that is longer and deeper than the supporting frame and which is wide and deep enough to extend across the top of the back of the chair and for a short distance down its back the two parts when 15 secured together forming a container. In the frame are openings and a central boss containing a spindle on which is a plate that is semi-rotatable and on part of which the word "Reserved" is printed, seen through a glazed opening in the frame. The spindle can be rotated by a key. In other openings are 20 marks to denote the number of the seat and row in which it is situated.

On the cover plate that combined with the light frame forms a container in which the information and mechanism can be housed is a central cowl behind which is an electric lamp the rays from which are deflected upon the floor or passageway behind the chair. 25 But in order to fully understand the invention, reference is made to the accompanying drawings in which,

Fig. 1 is an elevation of the front of the attachment.

Fig. 2 shows the same in rear elevation.

Fig. 3 is a side sectional elevation of the whole container, and

Fig. 4 an elevation of part of the container and semi-rotatable plate therein when the front is removed.

The light frame 5 is made attachable to the chair back 6 such as through the bracket 7 and is provided with a boss 8 that forms a bearing for a spindle 9 on which is a hollow attachment 10 within the boss. The hollow member is adapted to receive a key as for instance key 11 for the purpose of rotating the spindle. Also on the spindle is the semi-rotatable plate 12 on one part of which the word 50 "Reserved" is printed, the other half being

blank on which an advertisement or other information can be placed.

The light frame is composed of a plate in which are glazed openings the smaller openings being for the purpose of displaying the 55 mark of the row and chair number while through the largest opening the word "Reserved" is displayed when the plate is in the position indicated in Fig. 1.

In order to provide a compartment for the 60 plate 12 and the printed information, the cover plate 13 is attached to the member 5 by bolts 14, and in order to properly contain the parts plate 13 is extended downwards beyond the frame 5 to below the bracket 7. In the 65 plate are several glazed openings in the uppermost of which the back of the semi-rotatable plate 12 is seen. On this, two separate advertisements are placed, one of which can be read when the plate is moved to display the 70 word "Reserved" at the front and the other of which is disclosed when the reserved notice is masked.

Below the topmost opening are other glazed windows through which the row mark 75 and chair number are permanently seen. Beneath these again are other glazed openings behind which are advertisements and through openings in the wings or lateral extensions of the cover plate 13 other advertisements are 80 displayed.

In order to provide for easy access to the advertisements for changing same, the cover plate is readily removed from the fixed frame 5 by removing the bolts 14 and to change the 85 information on the front side of the semi-rotatable plate 12 same is held upon the spindle 9 by the nut 15 which is released before taking off the plate.

At about the center of the cover plate is 90 an inclining cowl 16 into which the rays from a lamp 18 set in the top of the back of the chair come through an opening 19 in the bracket 7 and another opening 20 provided in the cover plate behind the cowl. Outside 95 the cowl, a mirror 17 can be installed.

In operation, the attendant will carry the key 11 and will insert it in the hollow of 10 to set the reserved notice in the chair to which he will conduct the owner for the time being. 100

If the chair is not reserved, the notice will be masked to show the matter upon the other part of the plate 12. At the same time, the advertisements and information on the back 5 of the chair will be displayed and the lamp will shine through the openings 19 and 20 into the cowl which will deflect the rays upon the floor or passageway when the theater is in darkness.

- 10 The frame 5 and the cover plate 13 are each flanged and when screwed together by the bolts 14 constitute a container for the operative parts which container will extend below the frame to include the frame bracket. 15 The cover plate also extends laterally towards the sides of the chair back to provide other window openings for the display of advertisements.

Having now described our invention what 20 we claim as new and desire to secure by Letters Patent is:—

1. In an attachment to chairs of the kind indicated, a frame secured to the top of the back of a chair, a boss thereon, a spindle supported in the boss, a sectoral plate on the spindle within the frame adapted to be rotated with the spindle by a key, a cover plate over the frame extending below the same at the back of the chair and glazed openings in 30 the cover plate and frame.

2. In an attachment to chairs, a frame on the top of the back of a chair, a depending bracket on the frame secured to the chair back, a boss thereon, a spindle in the boss 35 and a sectoral plate on the spindle in combination with a cover plate constituting with the frame a compartment for the operative parts and glazed openings in the cover and frame.

40 3. In an attachment to chairs, a frame on the top of the back of a chair, a depending bracket on the frame secured to the chair back, a boss thereon, a spindle in the boss and a sectoral plate on the spindle in combination 45 with a cover plate constituting with the frame a compartment for the operative parts, a recessed socket piece secured on the outer end of the spindle adapted to fit into the boss and to take a key and glazed openings in the 50 cover and frame.

4. In an attachment to chairs, a bracketed frame on the back of a chair, a cover plate to the frame, a sectoral plate on a spindle in a boss adapted to semi rotary movements with- 55 in the compartment so formed, a cowl on the cover plate and a lamp behind the cowl, openings in the frame bracket and cover plate between the cowl and lamp, lateral wings on the cover plate that extend beyond the frame 60 over the back of the chair and glazed openings in the cover and frame.

65 5. In an attachment to chairs, a bracketed frame on the back of a chair, a cover plate to the frame, a sectoral plate on a spindle in a boss adapted to semi rotary movements with-

in the compartment so formed, a cowl on the cover plate and a lamp behind the cowl, openings in the frame bracket and cover plate, lateral wings on the cover plate that extend below and beyond the frame over the back of the chair, a recessed socket piece secured on the outer end of the spindle adapted to fit into the boss and to take a key and glazed openings in the cover and frame, as and for the purposes explained.

In testimony whereof we affix our signatures.

CHARLES HENLEY KNIGHT.
PHIL RANDALL.
